FLEXIBLE DRINKING STRAW

Harry E. Davis, 544 Vinita St., Akron, Ohio

Filed May 9, 1963, Ser. No. 74,818

Term of patent 14 years

(Cl. D2—3)

The figure is a perspective view of a flexible drinking straw showing my new design with a portion of the crinkled translucent outer wall broken way to disclose the substantially smooth inner contrastingly colored, decorative ribbon.

I claim:

The ornamental design for a flexible drinking straw, substantially as shown and described.
